UNITED STATES PATENT OFFICE.

HARRY EDWARD DOODY, OF BROOKLYN, NEW YORK.

EXTENSION-GRIP FOR CARS.

1,257,820.

Specification of Letters Patent. Patented Feb. 26, 1918.

Application filed November 2, 1917. Serial No. 199,353.

To all whom it may concern:

Be it known that I, HARRY EDWARD DOODY, a citizen of the United States, and a resident of the city of New York, borough 5 of Brooklyn, in the county of Kings and State of New York, have invented a new and Improved Extension-Grip for Cars, of which the following is a full, clear, and exact description.

10 My invention relates to a hanger or grip to be employed in street cars, railway cars, etc., in lieu of the hanger straps, and particularly the invention relates to an extensible hanger grip adjustable as to its length 15 to suit the reach of persons of different stature.

The invention has for its object to provide a telescoping hanger grip and novel means to permit of the extension movement 20 when desired.

Reference is to be had to the accompanying drawings forming a part of this specification in which similar reference characters indicate corresponding parts in all the 25 views, it being understood that the drawings are merely illustrative of one example of the invention.

Figure 1 is a side elevation of a hanger grip embodying my invention, the usual 30 car rod or rail being in cross section on the line 1—1, Fig. 2.

Fig. 2 is a longitudinal vertical section on the line 2—2, Fig. 1;

Fig. 3 is a horizontal section on the line 35 3—3, Fig. 2.

In carrying out my invention in practice, suitable suspension means are provided to suspend the device from the usual rail A of a car, there being shown a loop or strap 10 40 in the present instance. The suspension hanger 10 suspends telescoping elements, there being a relatively fixed casing 11 and an element 12 telescoping in the casing 11 and preferably made tubular for lightness.

45 On the lower end of the element 12, outside of the casing 11, is a hand-hold or grip 13, here shown in the form of a U-shaped loop or strap integral with said element 12 and presenting depending members at two sides 50 joined by a bent transverse portion 14 at the bottom.

A spring 15 is coiled about the element 12 in the space between said element and the casing 11, the spring bearing at its lower 55 end against an inturned flange 16 on the

casing 11 and at its upper end against an annular flange or collar 17 on the elements 12 below the top of the casing 11. The spring 15 tends to maintain the element 12 in the retracted position in the casing 11 60 and the inward movement of said element is limited by a stop flange 18 at the upper end of the handle 13, a washer 19 preferably being interposed between said flange 18 and a flange 16 on the casing 11. 65

I provide coacting members on the casing 11 and on the telescoping member 12 to resist extensible movement of the latter or to permit said extensible movement when desired for which purpose in the illustrated 70 example latches 20 are pivoted on the element 12 at the upper end thereof, preferably diametrically opposite, by horizontal pivots 21 and are under the pressure of springs 22 here shown as formed from a single element 75 secured to the top 23 of the element 12 and adapted to project the said latches laterally outward through slots or openings 24 formed in said element 12. In the laterally projecting positions of the latches 20 they lie 80 above fixed arcuate stops 25 on the casing 11 at the interior, so that by the engagement of the latches with the stops, outward movement of the element 12 is resisted and a person therefore holding onto the hand-hold 13 85 will be afforded firm support with the element 12 in the raised or retracted position which is suited to a person of average height. To effect an extension of the hanger, the telescoping element 12 may be turned 90 through an angle to dispose the latches 20 out of alignment with the stops 25, there being arcuate openings between said stops at diametrically opposite sides of the casing 11 to permit the latches 20 to clear the stops 95

in extending the handle by a downward pull on the hand-hold 13 against the tension of the spring 15, thereby placing the said spring under tension and positioning the latches 20 below the stops 25. The spring 15 thereby 100 tends to return the element 12 to the retracted position when the hand-hold 13 is released and the strength of said spring 15 is superior to that of the springs 22, whereby should the latches 20 be in line with the stops 25 105 in the upward movement of the element 12, the latches will be forced inwardly by engagement of their outer edges with the opposed edges of the said stops. The said outer edges of the latches it will be observed 110

are beveled to cause the inward movement of the latches in contacting with the stops 25 under the action of the spring 15.

I wish to state in conclusion that although 5 the illustrated example constitutes a practical embodiment of my invention, I do not limit myself strictly to the mechanical details herein illustrated, since manifestly the same can be considerably varied without departure 10 from the spirit of the invention as defined in the appended claims.

Having thus described my invention, I claim as new, and desire to secure by Letters Patent:

- 15 1. An extensible grip for cars, including a suspension hanger, a casing hung thereon, an elongated element telescoping in the casing, a hand-hold on said element below the casing, a spring within the casing and acting 20 on the said element tending to maintain the same in the retracted position, a stop on the said casing at the interior, below the top, a latch pivoted on the said telescoping element adjacent to the upper end to normally 25 lie above the stop, and a spring acting on said latch and tending to maintain the same in the path of the stop, the said telescoping element being adapted to be turned through an angle to aline the latch with the stop or 30 to position it out of line with the stop to clear the latter, and the first mentioned spring being of a strength to overcome the pressure of the latch spring and carry the latch past the stop in the retracting movement 35 of the telescoping element.

2. An extensible grip for cars, including suspension means, elements suspended from

the said means, one of said elements telescoping the other and provided with a hand-hold below the other element, spring means tending to maintain the telescoping element in retracted position, and coacting means on the respective elements adapted for engagement to resist relative longitudinal movement thereof, the said elements being 40 relatively turnable through an angle to disengage said coacting members and permit relative longitudinal movement of said elements to effect extension of the grip.

3. An extensible grip for cars, including 50 extension means, a casing thereon, a tubular element telescoping in the casing, a spring normally tending to maintain the element in retracted position, fixed stops on the casing at the interior, the said element having slots 55 disposed above the stops when the telescoping element is in retracted position, latches pivoted to said element and lying in the said slots, spring means tending to maintain the latches projecting beyond the slots 60 to be engaged with the stops, the outer edges of the said latches being beveled, and a U-shaped hand-hold on the telescoping element below the casing, said element being turnable in the casing to bring the latches into 65 or out of register with the stops for an outward movement of the said element, and the first mentioned spring being adapted to overcome the pressure of the spring means associated with the latches upon the beveled 70 edges of the latches contacting with the stops and upon an inward movement of the telescoping element.

HARRY EDWARD DOODY.
